UNITED STATES PATENT OFFICE.

W. H. CORE, OF NEW YORK, N. Y., ASSIGNOR TO HIMSELF AND A. LORENZ, OF SAME PLACE.

DESIGN FOR A SHOW-CASE.

Specification forming part of Design No. 1,567, dated April 22, 1862.

To all whom it may concern:

Be it known that I, W. H. CORE, of the city, county, and State of New York, have produced a new and ornamental Design for a Show-Case; and I do hereby declare that the following is a full, clear, and exact description of the same, reference being had to the accompanying drawings, forming a part of this specification, in which—

Figure 1 represents a front elevation of my design. Fig. 2 is a transverse vertical section of the same. Fig. 3 is a detached transverse section of one of its parts.

Similar letters of reference indicate corresponding parts in the several figures.

My new design refers to the base of a show-case, to its corners or pillars, and to the frame which forms its top.

The base A of my show-case B consists of a plinth a, which is surmounted by a cavetto b, the perpendicular height of which is about half that of the plinth. Above the cavetto b an inclined flat member c follows, about equal in width to the plinth, and said inclined member is surmounted by a torus d, the vertical height or diameter of which is about equal to the vertical height of the cavetto b, and which projects beyond the upper edge of the inclined member c, as clearly shown in Figs. 1 and 2 of the drawings. The torus d is followed by an ovolو e, which forms the upper edge of the base A. Said base is square or oblong, and it bears on its corners the pillars C, which support the top frame D. The pillars C are made with four flat sides f f' g g', as clearly shown in Fig. 3, which represents a transverse section of one of said pil-

lars. The sides g g' are about twice as long as the sides f f', and they join each other under a right angle, or nearly so, and the sides f f' under angles of about one hundred and thirty-five degrees. The corners g*, where the sides g g' join, are placed on the corners of the base, as clearly shown in Fig. 1. The pillars C support the top frame D, which is made square or oblong to correspond to the base A. The sides of the top frame D are made of bars h, a transverse section of which shows the form of an octagon, having three of its sides cut away, as clearly shown in Fig. 2. The rear side i of the top frame is made flat or oblong in the usual manner.

The base, the pillars, and the sides of the top frame of my show-case are intended to be made of sheet metal, which is brought in the required shape by means of suitable dies, and after it has been shaped said sheet metal is secured to strips of wood j k l, the shape of which corresponds to that part of the case to which they are to be attached, as clearly shown in Figs. 2 and 3 of the drawings.

Having thus fully described my design, what I claim as new, and desire to secure by Letters Patent, is—

The base A, consisting of a plinth a, cavetto b, inclined flat member c, torus d, and ovolو e; as shown and described, also the pillars C, with four sides g g' f f', connecting with each other, as shown and described, also the octagonal bars h of the top frame D.

W. H. CORE.
